ROBERT S. PERRY AND ARNO W. KARNOOPP, OF NEW YORK, N. Y.

FIRE-ARRESTING APPARATUS.

Application filed August 25, 1923. Serial No. 659,407.

Our invention relates to processes for fire-arresting and mechanical fire-arresting devices and refers particularly to processes and devices of that character particularly 5 suitable for employment with fumes carrying resinous or sticky materials.

The necessity for effective fire-arresting processes and for mechanical fire-arresting devices in apparatus carrying streams of inflammable fumes is generally recognized, and processes and devices of this character are particularly desirable in the production 10 of such materials as varnishes, lacquers, &c., in which the heat treatment of the combustible raw materials necessary in the production of the desired products causes the formation of inflammable fumes which, at the temperatures used in the heat treatment, are liable to ignite and thus lead to the combustion and loss of the said raw materials and therefore makes it desirable that the 15 said inflammable fumes be controlled in devices to protect them from admixture with sufficient oxygen of the air to support combustion and that they be protected from the localized temperatures and flames of the heat treatments and for all the above purposes that they be collected and conveyed away from the apparatus for heat treatment 20 in suitable conduits and under induced suction.

In the production of varnish, for instance, the raw materials are employed in comparatively small quantities, each batch being 25 heated in a kettle by means of direct fire, this small individual batch production being necessary under the conditions of varnish formation.

The fumes produced in each such operation 30 are conveyed from the upper portion of the kettles through conduits into the atmosphere or into devices for their further treatment of ingredient recovery or elimination of undesirable odors.

For economy of construction and ease of 35 operation, it is usually found desirable to convey the fumes from a series of such heating kettles into a manifold conduit, the manifolded fume streams being then further conveyed for final disposition.

Fumes of this character are highly inflammable, especially when mixed with quantities of air, and hence, it is evident that a fire originating in any portion of the thus 45 combined device may be continued and sup-

ported by the raw materials and the continually evolved fume and the admixture therewith of oxygen of the air drawing into the fume current by the induced suction, thus causing great damage and dan- 60 ger.

To overcome this increased fire danger, it has been suggested that mechanical fire arresting devices be introduced into each fume conveying conduit between the heating 65 kettle and the manifold conduit which will operate to cut off and isolate the particular unit in which the fire originates and in thus operating will also cut off from said unit the induced draft in order to stop the withdrawal of oxygen of the air and to thereby 70 smother and extinguish the fire.

In the production of varnish, for instance, the raw materials are comprised largely of gums and resin oils, which, when heated, 75 evolve fumes carrying materials of a sticky nature and this property of the heated fumes must be considered in the construction of mechanical fire-arresting devices for employment with such fumes. 80

Experience has shown that devices for this purpose comprising only a hinged door retained in open position by means of a fusible chain or link are liable to become partially, or totally, inoperative because of 85 the deposit of gums and sticky materials in and around the hinges, thus preventing the closure of the door upon the release of the retaining means and thereby continuing the induced draft to support combustion or 90 causing it to close so slowly as not to prevent the passage of ignited fumes through the device and into the manifold and the other connected fume conduit units.

It is evident that the closure device must 95 act effectively to entirely cut off the draft to prevent air being indrawn to mix with the ignited mixture and must act promptly and effectively to prevent the passage of these moving ignited fumes and that a delay 100 of operation, though it may be slight, will defeat the purposes for which the device is employed.

The device of our invention overcomes all 105 of these dangerous imperfections of mechanical fire-arresting devices and presents a positive means for preventing the passage of ignited fumes beyond the device and positive means for smothering a fire in that portion of the fume producing compart- 110

ment in which it originated and in that portion of the fume controlling conduits anterior to the device of our invention.

In the accompanying drawings, illustrating modifications of the device of our invention, similar parts are designated by similar numerals.

Figure 1 is a vertical cross-section of one form of a device of our invention.

10 Figure 2 is a vertical cross-section of one form of a device of our invention.

Figure 3 is a section through the line 3—3 of Figure 2 with the fume control cover in closed position.

15 The particular form of the device of our invention, shown in Figure 1, comprises a cylindrical fume chamber 10 open at the bottom and closed at the top by the cover 11 having the hand-hole 12. The fume chamber is supported by the annular base 13, the inner face of which is inclined downwardly and centrally toward the opening 14, to which is attached a conduit 15, the jointure between the fume chamber and the base being of such a character as to prevent the escape of fumes therethrough. The conduit 15 is attached to, or carries means (not shown) by which an induced draft can be produced therein, the fumes, air and gases 20 being thus drawn through the conduit 16 and the fume chamber 10. A conduit 16 connects the interior of the fume chamber 10 with a source of fume supply, not shown.

30 Pivotedly attached at 17 to the arm 18, which is fixedly attached to the base 13, is a closure member comprising the arm 19 and the cover proper 20. The fume control cover 20 is of such size, shape and position that it will completely cover the opening 14 when 35 it is in lowered position, as shown by the dot-and-dash lines 19' and 20'.

The drawing shows only one arm 18 and one arm 19, but I prefer to employ two spaced arms 18 carrying a rod 17 to which are pivotedly attached two arms 19 connected with the fume control cover 20 in a manner similar to the construction shown in Figures 2 and 3.

50 The hook 21 carried by the top 11 carries the fusible link 22, which, in turn, carries the weight 23, which, in turn, is connected to the lip 24 of the arm 19, holding the fume control cover 20 in raised position and allowing free passage of fumes through the pipe 16, into the fume chamber 10 and outwardly through the opening 14 and the conduit 15.

When the device is in operation and the fumes are in normal condition, they pass 60 through the pipe 16, the chamber 10 and the conduit 15, thus allowing of their free movement through the device. In the event of the ignition of the fumes, the heat thus generated melts the fusible link 22, allowing 65 the weight to fall with impact force upon

the top of the fume control cover 19 and 70 20, causing it to drop and be positioned as shown in the dot-and-dash lines, thus completely covering the opening 14 and preventing the passage of the ignited fumes beyond the fume chamber 10 and stopping the action of the induced draft in that portion of the flue system in front of the cover 20.

The particular form of the device of my invention, shown in Figures 2 and 3, comprises an entrance conduit 25 connected to the fume chamber 26, which, in turn, is connected to the exit chamber 27, which is connected to the exit conduit 28, the whole device being inclined downwardly toward the exit conduits 28, for reasons described later.

Positioned within the fume chamber 26 and transversely thereof is a partition 29 having an opening 30 which extends downwardly to the bottom of the fume chamber. 85 The partition 29 is attached to the walls of the fume chamber and is supported by the annular angle-iron 31 which is broken away at the bottom portion of the chamber.

90 Fixedly attached to the upper portion of the partition 29 are two spaced angle-iron plates 32, 32, the extended portions of which carry the rod 33. Pivotedly carried by the rod 33 is a fume control cover comprising the two angle-iron arms 34, 34 and the cover proper 35. The size, shape and position of the fume control cover is such that it will completely cover the opening 30 of the partition 29, preventing the passage of fumes from the fume chamber 26 into the exit 100 chamber 27.

A wire 36 attached to the wall of the fume chamber 26 is connected to the fusible link 37 which, in turn, is connected to the wire 38 passing over the idler 39, the other extremity of the wire 38 being connected to the weight 40. A wire 41 is attached to the rod 33 and the weight 40, and another wire 42 is attached to the bolt 43 of the cover 35 and the weight 40.

110 The several described elements are so positioned as to hold the fume control cover in raised open position, as shown in Figure 2.

115 When the device is operating and the fumes are in normal position they pass freely through the device in the direction of the arrows and any condensed or deposited liquid matters will flow along the lower portion of the fume chamber through the opening 30 and thence outwardly. If the entering fumes become ignited, the heat thus generated will melt the fusible link 37, allowing the weight 40 to fall with impact force upon the top of the fume control cover causing it to drop and be positioned as shown in the dot-and-dash lines in Figure 2, thus completely covering the opening 30 and preventing the passage of the ignited fumes beyond the fume chamber 26 and stopping 120 125 130

the action of induced draft in that portion of the flue system in front of the cover 35.

In order to give access to the device, the side of the fume chamber 26 carries an opening 44, upon each side of which is a slide guard 45, within which the cover 46 having the handle 47 is slidable and is of such size and shape as to completely cover the opening 44.

10 It will thus be seen that the fumes have free passage through my device under desirable normal working conditions but that upon the ignition of the fumes the fume control cover is released and is given an impact blow to overcome any inertia it may have due to the deposit and accumulation of gummy and sticky matters upon the pivotal point of the cover, thus causing it to move and to be positioned across the exit opening, thus preventing the passage of the ignited fumes beyond the fume control chamber and preventing the further action of the induced draft of the general system to function back of the cover.

15 20 25 It will also be noted that in the modifications shown, the impact weight will rest upon the cover in its closed position, thus

increasing the effectiveness of the jointure, although this particular element of operation is not always necessary. By "impact" 30 we mean a sudden blow delivered to the closure cover caused by the impact of a falling body.

We do not limit ourselves to the particular size, shape, number or arrangement of 35 parts as shown and described, as these are given simply as a means for clearly describing the device of our invention.

What we claim is:—

In a mechanical fire-arresting device, in 40 combination, a fume conduit; a gravity operative closure for said conduit; a weighted means retaining said closure from across the conduit, the weight being spaced from the closure, and fusible means suspending 45 the weight, the melting of which will cause the weight to fall upon the closure, the closure being thus released to close the conduit.

Signed at New York city in the county of New York and State of New York this 22nd 50 day of August, 1923.

ROBERT S. PERRY.
